CLAIM

The ornamental design for a container lid, as shown and described.

DESCRIPTION

FIG. 1 is a top front right perspective view of our new, original, and ornamental design for a container lid.

FIG. 2 is a front view thereof.

FIG. 3 is a rear view thereof.

FIG. 4 is a left side view thereof, the right side view being a mirror image thereof.

FIG. 5 is a top view thereof; and,

FIG. 6 is a bottom view thereof.

The dashed lines illustrate portions and environment of the container lid that form no part of the claimed design.

1 Claim, 6 Drawing Sheets
